Attorney

UNITED STATES PATENT OFFICE

JOSEPH J. SANDERS, OF PHILADELPHIA, PENNSYLVANIA, ASSIGNOR TO H. BRINTON COMPANY, OF PHILADELPHIA, PENNSYLVANIA, A CORPORATION OF PENNSYLVANIA

DESIGN WHEEL

Application filed July 8, 1931. Serial No. 549,558.

My said invention relates to a design wheel and it is an object thereof to provide grooved means whereby the operation of the design wheel may be changed in much less time than 5 has heretofore been the case. In design wheels of this character inserts are ordinarily held between two rigid pieces of metal and when the set up of the design wheel is to be changed it is necessary to remove the cover 10 and then to put in or take out inserts as desired for the particular set up to be performed. In the present wheel a complete set of inserts is put into the wheel and they are then moved to active or inactive position as 15 desired.

Referring to the drawing, which is made a part of this application and in which similar reference characters indicate similar parts:

Fig. 1 is a plan of the wheel of my invention,

Fig. 2, a section on line 2—2 of Fig. 1,

Fig. 3, a section of one element of the wheel, taken on line 3—3 of Fig. 3,

Fig. 4, a plan of a resilient disk forming 25 one element of the invention,

Fig. 5, a perspective of an insert on an enlarged scale, and

Fig. 6, a fragmentary elevation of the wheel.

30 In the drawing reference character 10 indicates the body member of the wheel which, in the present embodiment, is shown as provided with notches at 11, these notches being inclined with reference to the axis of the 35 wheel for the reason that the wheel of the present embodiment is such a wheel as is commonly mounted alongside a needle cylinder on an axis inclined to that of the cylinder, so that needles whose butts rest on the inserts 40 hereinafter described will be lifted whereas the butts of the other needles engage in the notches and merely assist in rotating the wheel but are not lifted thereby. Fig. 3 shows 45 a section of said body through the teeth between the notches.

In addition to the notches 11 the wheel is provided with radial slots in which inserts 12 are mounted for inward and outward movement relative to the axis of the wheel. These 50 inserts are each provided with an outer lift-

ing portion 13, a lug 14 by means of which they may be moved in and out, notches at 15 and 16 for engagement with a holding device to be described and a lug 17 adapted to engage a ledge at 18 (Fig. 3) for limiting the outward 55 movement of the inserts.

A disk 19 of spring metal is journaled on the axle 20 of the wheel, said disk having an annular rib 21 for engaging with either one of the notches 15 and 16. The axle 20 extends 60 through the center opening of the body 10, as shown in Fig. 2, and has screw-threads co-operating with threads on a nut 22. By this means the parts are locked together and preferably a cover plate 23 is provided between 65 the nut and the resilient disk 19 for securely clamping the disk in place and preventing undue flexing of the disk.

In the use of my device I provide the same with a full complement of inserts in every 70 notch of the wheel. When such a wheel is used for lifting needles all the inserts at the points where needle butts are to be engaged for lifting them are moved out into the position indicated at 24 in Fig. 1 and also shown 75 in Fig. 2. Such inserts as are not to lift needles are moved back to the position indicated at 25 in Fig. 1, whereby the notches in the wheel are left open for engagement by the needle butts to turn the wheel. It will 80 be seen that no dismantling of the wheel is necessary but that designs may be changed very quickly by merely moving the inserts in or out in accordance with the desired pattern. It will be obvious also that the principle of 85 the invention may be utilized in many design wheels other than the specific type here illustrated and many changes may be made in the device, all without departing from the spirit of my invention, therefore I do not limit myself to what is shown in the drawing or described in the specification but only as indicated in the appended claims.

Having thus fully described my said invention, what I claim as new and desire to secure 95 by Letters Patent is:

1. In a design wheel, a body member having radially extending slots in a side face thereof, inserts in said slots movable into an outer active position or an inner inactive position.

sition, a resilient disk bearing on the inner ends of said inserts, and rigid means for holding the disk in place.

2. A device as in claim 1, said inserts having notches corresponding to the two positions thereof, and said disk having an annular rib for engagement with either one of said notches in an insert.

In testimony whereof I affix my signature.

JOSEPH J. SANDERS.
